UNITED STATES PATENT OFFICE.

EMERY M. McVICKER, OF MILWAUKEE, WISCONSIN, ASSIGNOR TO J. F. McVICKER, OF MILWAUKEE COUNTY, WISCONSIN.

RAIL ANCHOR.

Application filed August 2, 1926. Serial No. 126,440.

This invention relates to anti-creepers for railway rails.

In my prior Patent No. 1,551,503, issued August 25, 1925, and in my copending application Serial No. 99,476, filed April 3, 1926, I have described several forms of devices for holding railway rails against creeping. In each of the several forms the device is securely bound to the rail by a wedge driven into position against the top face of the rail flange. Although such devices have proven quite successful I have discovered that the flat form of wedge heretofore employed is not readily conformable to variations in inclination of the top face of the rail flange, with the result that full surface contact between the wedge and rail is not always obtainable. Under such conditions the wedging pressure is applied over a rather limited surface area thus impairing the gripping or binding action.

One object of the present invention is the provision of a wedge for the purposes mentioned so shaped as to avoid the above objections.

Various forms of anti-creepers have heretofore been designed which react directly against the tie to sustain the end thrust of the rail. Such devices ordinarily function to resist creeping in one direction only. Another object of the present invention is the provision of means for rendering anti-creepers of that type operable to resist creeping in both directions.

Various forms of anti-creepers have also been designed for positioning beneath the rail and engageable with the opposite sides thereof. Such devices have not proven entirely successful due to a tendency to work loose and fall from the rail. Some depend for their gripping power upon the inherent resiliency of the metal thereof, but the severe strains imposed on the metal results in fatigue with the result that they soon become loose. The use of wedges as a securing means for devices of this type has not heretofore proven successful because of the severe wear to which such wedges, as heretofore applied, are exposed. Another object

improved means for firmly binding or anchoring an anti-creeper of the type mentioned to a rail.

Other objects and advantages will appear from the following description of several 55 illustrative embodiments of the present invention.

In the drawings:—

Figure 1 is a plan view of an anti-creeper device for railway rails embodying the present invention.

Fig. 2 is a side elevation.

Figs. 3 and 4 are similar views, in plan and elevation, respectively, of a somewhat different form of anti-creeper, embodying 65 novel features of the present invention.

Fig. 5 is a view in elevation looking from left to right in Figure 4.

Fig. 6 is a view in elevation of a third form of anti-creeper embodying novel features of the present invention.

Fig. 7 is a fragmentary plan view, partly in section, of the anti-creeper of Figure 6.

The anti-creeper illustrated in Figures 1 and 2 comprises a body portion 10, preferably of bar form, and provided with a depending portion 11 adapted to abut the vertical face 12 of a tie 13. The body portion 10 is shown applied beneath and against the base flange 14 of the rail, and provided 70 at one end with an integral upstanding portion 15 shaped to provide a hook or jaw 16 overlying the flange. The jaw 16 cooperates with the body portion 10 to provide a recess 17 for receiving and embracing the edge 18 85 of the flange. The other end of the body portion is also provided with an integral upstanding portion 19 presenting a shoulder 20 for engagement with the edge 21 of the flange. A wedge 22 driven into wedging 90 engagement between the jaw 16 and the top of the rail flange securely binds the body portion to the rail, and the shoulder 20 serves to hold the body portion against movement laterally of the rail, so as to retain the 95 embracing recess 17 in gripping position thereon.

Sufficient clearance is provided between the jaw and the top of the rail flange so that, until the wedge has been applied, the 100

body portion 10 is free to swing toward or from the base of the rail, as indicated in dotted lines in Figure 2, about the edge 18 of the flange as a fulcrum, thus permitting easy application or removal of the body portion. By driving the wedge 22 into position, however, the body portion is rocked upwardly into firm contact with the base of the rail and the shoulder 20 engaged with the other edge 21 of the flange.

It will be noted that, as the rail tends to creep in the direction of the arrow, the engagement of the portion 11 against the face of the tie tends to rock the body portion in such direction as to increase the grip between the embracing recess 17 and the rail flange, and creeping is thus effectively prevented. It will also be noted that in this slight rocking action the jaw 16 acts as a fulcrum, so that there is no rubbing contact between the jaw and wedge. This peculiar relation explains the absence of wear on the wedge.

The wedge 22 shown is of novel form. It is tapered from end to end and formed with a substantially flat bottom face 23 for contact with the rail and a transversely curved top face 24 for contact with a similarly formed seat 25 in the face of the jaw 16. This curved formation of wedge and seat permits the wedge to automatically accommodate itself to variations in inclination of the top face of the rail flange, so as to effect full face contact therewith.

The device thus far described is well adapted to effectively hold the rail from creeping in the direction of the arrow, but to resist creeping in the other direction requires the addition of other means. To this end a plate 26 is provided which extends across the tie 13. The opposite ends of this plate are bent downwardly to provide tongues 27 and 28 adapted to bear against the vertical face 29 of the tie and the exposed side face of the upstanding portion 19, respectively. The plate is ordinarily applied over the edge of the rail flange, as indicated in Figures 1 and 2 and secured in position by any appropriate means, such as a spike 30. The arrangement is such that when the rail tends to creep in a direction opposite to the arrow, the tongue 28 reacts against the upstanding portion 19 of the anti-creeper to hold the same against movement away from the tie, and the stress thus imposed upon the plate is sustained mainly by the engagement of the tongue 27 thereof against the face 29 of the tie.

The anti-creeper illustrated in Figures 3, 4 and 5 is similar to that just described in that it includes a similar body portion 10' disposed beneath the base flange 14 of the rail, an upstanding portion 15' forming a jaw 16' overlying one edge of the flange, an upstanding portion 19' presenting a shoulder

20' for engagement with the other edge of the flange, and a depending portion 11' for engagement with a vertical face of the tie 13. A wedge 22' is also interposed between the jaw 16' and the top of the flange for binding the anti-creeper to the rail. In this instance however a tie plate 31 is employed so disposed between the rail and tie as to project slightly beyond the face of the tie, and a shoulder 32 is formed on the depending portion 11' for cooperation with the projecting edge of the tie-plate to prevent the anti-creeper and rail from lifting out of place. This anti-creeper functions in a manner similar to the device hereinabove described to prevent the rail from creeping in the direction of the arrow. A plate 26' is also provided for preventing creeping in the opposite direction. The plate 26' in this instance is superimposed upon the tie plate 31 and anchored to the tie by a spike 33. A recess 34 is formed in the plate 26' for embracing the upstanding portion 15' to thereby hold the same to the tie as the rail tends to creep in a direction opposite to the arrow.

The anti-creeper shown in Figures 6 and 7 is designed for engagement with one edge of the rail flange only, and is ordinarily employed with a tie plate 31''. It includes a body portion 10'' for engagement beneath the rail, an upstanding portion 15'' providing a jaw 16'' overlying the edge of the rail flange 14 and a depending portion 11'' for engagement with the vertical face of the tie 13. A wedge 22 is interposed between the jaw 16'' and the top of the flange to bind the anti-creeper to the rail. In this instance, however, the tie plate 31'' serves to hold the anti-creeper to the rail. To this end the tie plate is so positioned as to project slightly beyond the tie and is provided with a recess 35, in the overhanging edge thereof to receive and position the anti-creeper. The mouth 36 of the recess is preferably reduced to provide a shoulder 37 for holding the anti-creeper to the tie, but at the same time is of sufficient width to admit the anti-creeper and to permit the same to be turned into the working position shown. The depending portion 11'' reacts against the face of the tie in a manner similar to that above described to hold the rail against creeping in the direction of the arrow, and the body portion 10'' reacts against the shoulder 37 to hold the rail from creeping in the opposite direction. The depending portion 11'' is also preferably provided with shoulders 38 for cooperation with the overhanging portion of the tie plate to prevent the anti-creeper and rail from lifting or rocking out of place.

Various changes may be made in any of the embodiments of the invention hereinabove specifically described without depart-

ing from the invention as defined in the appended claims.

I claim:

1. An anti-creeper for railway rails comprising a member having an integral portion engageable beneath a base flange of a rail, an integral portion overlying the flange, and a wedge interposed between said last named portion and the top face of the flange for effecting a vertical gripping pressure therebetween, said wedge having a transversely curved surface coacting with said last named portion to permit the wedge to accommodate itself to variations in the inclination of said face.

2. An anti-creeper for railway rails comprising a member having an integral portion engageable beneath a base flange of a rail, an integral portion overlying said flange, a wedge interposed between said last named portion and the top face of said flange, for effecting a vertical gripping pressure between said member and flange said wedge having a transversely curved surface, and a curved seat in said last named portion for receiving said curved surface.

3. An anti-creeper for railway rails comprising a member having a portion for embracing an edge of a base flange of a rail, said portion including an integral element overlying the top face of the flange, a wedge interposed between said element and the top face of the flange for effecting a vertical binding pressure between said member and flange, said wedge having a transversely curved surface, and a curved seat formed in said element for receiving said wedge.

4. An anti-creeper for railway rails comprising a member having a portion engaging with and beneath a base flange of a rail, a portion engageable with a vertical face of a tie, and a portion overlying the flange, and a longitudinally tapered wedge having a transversely curved surface interposed between said last named portion and flange to effect a positive gripping pressure vertically applied between said member and rail.

5. An anti-creeper for railway rails comprising a member having a portion engaging with and beneath a base flange of a rail, a portion engaged with one edge of the flange, and a portion overlying the opposite edge of the flange, and a wedge having a transversely curved surface interposed between said last named portion and flange to bind said member to the rail, said overlying portion having a curved seat for rockably receiving and retaining said wedge.

6. An anti-creeper for railway rails comprising a member having a portion engaging with and beneath a base flange of a rail, a portion engaged with one edge of the flange, and a portion overlying the other edge of the flange, and a longitudinally tapered wedge interposed between said overlying

portion and the top face of the flange to lift and solidly retain said first named portion in positive binding contact with the flange.

7. An anti-creeper for railway rails comprising a member disposed transversely beneath a base flange of a rail, a shoulder adjacent one end of said member engaging a vertical edge only of the flange, a jaw adjacent the other end of said member overlying the other edge of the flange, and a wedge interposed between said jaw and the top face of the flange and coacting with said top face to lift and retain said shoulder in engagement with said cooperating vertical edge.

8. An anti-creeper for railway rails comprising a member disposed transversely beneath a base flange of a rail, an upstanding portion adjacent one end of said member engaging one side of the flange, a jaw adjacent the other end of said member overlying the other side of the flange, a tie engaging portion depending from said member directly beneath said jaw, and a longitudinally tapered wedge interposed between said jaw and the top face of said flange for solidly binding said member to the rail.

9. An anti-creeper for railway rails comprising a member disposed transversely beneath a base flange of a rail, an upstanding portion adjacent one end of said member engaging one side of the flange, means adjacent the other end of said member coacting with the other edge of the flange to secure said member to the rail, a tie engaging portion cooperating with the tie to hold the rail from creeping in one direction, and means cooperating with said member and tie to hold the rail from creeping in the opposite direction.

10. An anti-creeper for railway rails comprising a member having an integral upstanding portion at one end thereof for engagement with an edge of a base flange of a rail, an integral upstanding portion at the other end thereof for cooperation with the other edge of the flange, a wedge coacting with said last named portion to secure said member to the flange, and means cooperating with said member and tie to hold the rail from creeping in both directions.

11. An anti-creeper for railway rails comprising a member shaped to embrace an edge of a base flange of a rail, a wedge cooperating with said member to bind the same to the flange, said member having a portion for coaction with the vertical face of a tie to retain the rail from creeping in one direction, and means coacting with said member and tie to retain the rail from creeping in the opposite direction.

12. An anti-creeper for railway rails comprising a member disposed beneath the base flange of a rail, means on said member for engaging one edge of the flange, means on said member for engaging the other edge of

the flange to thereby secure said member to the rail, a tie plate, and a shoulder on said member engageable with said tie plate to prevent undue lifting or rocking of the rail.

5 13. An anti-creeper for railway rails comprising a member disposed beneath the base flange of a rail, means on said member for engaging the opposite edges of the flange to secure said member to the rail, means on said

member cooperating with a tie to retain the 10 rail against creeping, a tie plate, and a shoulder on said last named means cooperating with said tie plate to prevent undue lifting or rocking of the rail.

In witness whereof, I hereunto subscribe 15 my name this 29 day of July, 1926.

EMERY M. McVICKER.
